Herbert A. Rose, Leonia, N. J., assignor to Westinghouse Electric & Manufacturing Company, East Pittsburgh, Pa., a corporation of Pennsylvania

Application April 24, 1937, Serial No. 138,819

20 Claims. (Cl. 175—363)

My invention relates to an excitation system for a vapor electric device, and particularly to an excitation system having a static starting means.

In the operation of vapor electric converters, such as rectifiers, it has been customary to use an excitation electrode supplied with current from a suitable auxiliary source and to draw the arc from this exciting electrode to the cathode of the device by means of suitable mechanism which establishes contact between the exciting electrode and the cathode and then breaks this connection to initiate a keep-alive arc. This use of a mechanically moving part in an otherwise static device is highly unsatisfactory as the repeated operations may injure or even destroy the starting mechanism where the remainder of the device is in satisfactory working condition. There has recently been discovered a new starting principle wherein a current is passed through a body of resistance material in contact with the cathode to initiate a cathode spot at the beginning of any conducting period.

It is an object of my invention to provide an excitation system in which a keep-alive electrode has connected in series therewith a suitable resistance body or make-alive electrode, and to provide a source of excitation potential which will apply at the moment of starting a sufficiently high potential to initiate a cathode spot after which the excitation arc continues to burn through the keep-alive electrode at a somewhat reduced potential, preferably at a potential which produces a relatively unimportant current through the make-alive electrode.

It is a further object of my invention to provide an excitation system having an auxiliary source of keep-alive potential provided by the operation of the converter itself such as a potential derived from the harmonics generated in the converter or a potential derived from a stabilizing device such as an interphase transformer.

It is a further object of my invention to provide an excitation system using normally waste or dissipated energy to provide the excitation current.

Other objects and advantages of my invention will be apparent from the following detailed description, taken in conjunction with the accompanying drawings, in which:

Figure 1 is a schematic illustration of a conversion system utilizing my excitation system.

Fig. 2 is a similar view showing a modification according to my invention.

Figs. 3 and 4 are similar views showing the method of utilizing excitation currents from the operating values of the converter; and,

Fig. 5 is a diagrammatic illustration of the voltages and currents applied to the excitation electrodes.

In the illustrative embodiment of my invention according to Fig. 1, a vapor electric device such as a multi-anode rectifier 1 feeding a direct current circuit 2 is supplied from an alternating current circuit 3 by means of a suitable transformer arrangement 4 herein illustrated as double three-phase with interphase, although any suitable transforming device may be utilized. In the converter 1 is provided a suitable excitation electrode 5 spaced from the cathode 6 of the device 1 and having mechanically connected thereto and extending into contact with the cathode a suitable body 7 of resistance material suitable for forming a make-alive electrode. While any suitable material may be used for this resistance body, I have found that carborundum crystals, or a formed body of boron and carbon in the nature of boron carbide are particularly useful. A suitable source of excitation current is provided herein illustrated as an excitation transformer 8 deriving energy from the alternating current circuit 3, either directly or through a suitable operating transformer 9. The output potential of the excitation transformer 8 is rectified by a suitable rectifying device 10 and connected between the excitation electrode 5 and the cathode 6 of the device 1. Preferably, the excitation circuit is provided with a current limiting resistor 11 and a stabilizing reactor 12 in order to control and limit the exciting current.

In the operation of the system according to my invention, the exciting transformer 8 is energized and the resultant potential rectified by the rectifying device 10 when applied to the exciting electrode 5 and the cathode 6 of the device 1, so that the rectified potential appears across the make-alive electrode 7, the exciting transformer 8 having a sufficiently high potential to cause sufficient current flow through the make-alive electrode 7 to initiate a cathode spot on the cathode 6 of the device 1 after which a keep-alive arc will be struck from the exciting electrode 5 to the cathode 6 of the device. Preferably, the excitation transformer 8 is provided with a high regulation characteristic so that after the excitation arc has begun to burn, the terminal voltage will be reduced to a level sufficient to maintain the keep-alive arc but at a

value which does not produce objectionable currents in the make-alive electrode 7.

If desired, the keep-alive electrode is divided into two parts, one portion 14 of the keep-alive electrode being in the vicinity of the anodes 15 to be excited. Preferably a resistor 16 of suitable value is connected between these keep-alive electrodes 5 and 14 so that after the device has become excited, the major portion of the keep-alive arc will transfer to the exciting electrode 14 adjacent the anodes 15.

In the modification according to Fig. 2 I have provided a plurality of similar excitation electrodes 5, preferably each being provided with a suitable make-alive electrode 7 and apply the output potential of the excitation transformer 8 directly to the keep-alive electrodes 5 without the necessity of an intervening rectifying device. The operation of this form of the invention is substantially identical with that described above except that the keep-alive arc transfers between the excitation electrodes 5 with the alternations of the potential supplied by the excitation transformer 8.

25 In the modification according to Fig. 3, an initial keep-alive arc is struck in the manner shown in Fig. 1 as described above. However, a plurality of auxiliary exciting electrodes 25 are provided, preferably each of these auxiliary electrodes 25 being also provided with a suitable make-alive electrode 7. These auxiliary electrodes 25 are supplied with potential from a transformer 26 energized at a frequency which is a harmonic of the frequency supplied to the main anodes 15 of the device 1 and being derived from a circuit 27 connected across the direct current circuit 2 fed by the converter 1. This circuit comprises a suitable capacitor 28 and a reactor 29 forming the primary of the auxiliary excitation transformer 26. While suitable operation may be obtained with an untuned circuit, it is frequently found desirable to tune this auxiliary circuit 27 to a suitable harmonic generated by the converter 1. Preferably this auxiliary excitation source is connected ahead of the usual telephone filter circuits which generally include a series reactor 31 in the direct current circuit 2 and suitable shunt filters 32 across the circuit 2. I prefer to provide the initial keep-alive circuit with a suitable contacting device 33 which will be operative to disconnect the initial keep-alive circuit when the current through the converter 1 is sufficient to provide the necessary excitation current from the auxiliary source 36.

55 In the embodiment of my invention according to Fig. 4, the auxiliary electrodes 25 are connected to an auxiliary winding 35 on the interphase transformer 36 which is excited by the exciting current of the interphase transformer. Preferably the control device 33 for deenergizing the primary exciting circuit is so regulated that this primary circuit will not be interrupted until after sufficient current flows to excite the interphase transformer 36 so as to eliminate any danger of the primary circuit being interrupted before the actual operation of the auxiliary keep-alive circuit 35 and to insure that the primary circuit will be again connected before termination of the flow of exciting current from the auxiliary source 35.

According to the diagrammatic illustration in Fig. 5, it is seen that the exciting transformer 8 has a step regulation characteristic so that prior to current flow in the exciting electrodes 5, a sufficiently high potential 46 will be supplied to

the make-alive electrodes 7 to insure their operation to create a cathode spot. However, when current begins to flow in the keep-alive electrode the voltage decreases as shown by the curve 41 to a point 42 sufficient to maintain the keep-alive arc but insufficient to provide operating current for the make-alive electrode 7. After the main arcs of the converter are established, the strong ionization in the device 1 permits an increase of current in the keep-alive arc which further reduces the potential supplied by the excitation transformer as shown at 43.

While for purposes of illustration I have shown and described specific embodiments of my invention, it will be apparent to those skilled in the art that many changes and modifications can be made therein without departing from the true spirit of my invention and the scope of the appended claims.

I claim as my invention:

20 1. An electric current converting system comprising an alternating current supply circuit, a vapor-electric device having a plurality of anodes and a vaporizable cathode, transformer means for supplying potential from said alternating current circuit to said anodes, a direct current circuit connected to said device, a keep-alive electrode in said device, a body of material suitable for operation as a make-alive electrode electrically connected to said keep-alive electrode and extending between said keep-alive electrode and the cathode of said device, a source of keep-alive potential and connections for impressing said potential between said keep-alive electrode and said cathode.

25 2. An electric current converting system comprising an alternating current supply circuit, a vapor-electric device having a plurality of anodes and a vaporizable cathode, transformer means for supplying a potential from said alternating current circuit to said anodes, a direct current circuit connected to said device, a keep-alive electrode in said device, a body of material suitable for operation as a make-alive electrode extending between said keep-alive electrode and the cathode of said device said body being electrically connected to said keep-alive electrode, an auxiliary source of alternating current, means for rectifying current from said source and connections for impressing said rectified current between said keep-alive electrode and the cathode of said device.

30 3. An electric current converting system comprising an alternating current supply line, a vapor electric device of the arcing type having a plurality of anodes and a vaporizing cathode, transformer means for supplying potential to the anodes from said supply line, a direct current circuit supplied by said device, an excitation electrode in said device, said electrode being spaced from said cathode, a body of resistance material electrically connected to said electrode and extending into contact with said cathode and means for supplying exciting current between said electrode and said cathode.

35 4. An electric current converting system comprising an alternating current supply line, a vapor electric device of the arcing type having a plurality of anodes and a vaporizing cathode, transformer means for supplying potential to the anodes from said supply line, a direct current circuit supplied by said device, an excitation electrode in said device, said electrode being spaced from said cathode, a body of resistance material electrically connected to said electrode and ex- 75

tending into contact with said cathode and means for supplying exciting current between said electrode and said cathode, said resistance body having a resistance such that the potential necessary to maintain an arc between said exciting electrode and said cathode will produce only a relatively small current in said resistance body.

5. An electrical conversion system comprising an alternating current circuit, a direct current circuit, a vapor electric device including a plurality of anodes and a vaporizable cathode, transformer means including an interphase transformer for supplying current to said device, an exciting electrode in said device, a source of exciting current connected to said electrode, means for initiating an exciting arc between said electrode and the cathode, a plurality of auxiliary exciting electrodes in said device, an auxiliary winding on said interphase transformer and means for connecting said auxiliary winding to said auxiliary electrodes.

6. An electrical conversion system comprising an alternating current circuit, a direct current circuit, a vapor electric device including a plurality of anodes and a vaporizable cathode, transformer means including an interphase transformer for supplying current to said device, an exciting electrode in said device, a source of exciting current connected to said electrode, a make-alive electrode electrically connected to said electrode and extending into contact with the cathode for initiating an exciting arc between said electrode and the cathode, a plurality of auxiliary exciting electrodes in said device, an auxiliary winding on said interphase transformer and means for connecting said auxiliary winding to said auxiliary electrodes.

7. An electric current conversion system comprising two dissimilar electrical circuits, a multi-valve vapor electric converter for transferring energy between said circuits, an exciting electrode in said converter, a rod of high resistance material extending between said exciting electrode and the cathode of said converter said rod being electrically connected to said exciting electrode and means for impressing an exciting potential between said exciting electrode and the cathode of said converter.

8. An electric current conversion system comprising two dissimilar electrical circuits, a multi-valve vapor electric converter for transferring energy between said circuit, an exciting electrode in said converter, a rod of high resistance material extending between said exciting electrode and the cathode of said converter, said rod being electrically connected to said exciting electrode, means for impressing an exciting potential between said exciting electrode and the cathode of said converter, an auxiliary exciting electrode in said converter and means for transferring a major portion of the exciting current from said first mentioned exciting electrode and said auxiliary exciting electrode.

9. An electrical translating system for transferring electrical energy between two dissimilar electrical circuits, one of which is an alternating current circuit comprising an arc type converter including a plurality of main electrodes one of which is a vaporizable cathode, transformer means for connecting said converter to said circuits, a keep-alive electrode in said converter, a source of exciting current connected to said keep-alive electrode and said cathode, make-alive means for initiating the flow of exciting current in said device, a plurality of auxiliary keep-alive

electrodes in said converter, a second source of exciting current energized by current flow in said converter and means for connecting said second source of current to said auxiliary keep-alive electrodes.

10. An electrical translating system for transferring electrical energy between two dissimilar electrical circuits, one of which is an alternating current circuit comprising an arc type converter including a plurality of main electrodes one of which is a vaporizable cathode, transformer means for connecting said converter to said circuits, a keep-alive electrode in said converter, a source of exciting current connected to said keep-alive electrode and said cathode, make-alive means for initiating the flow of exciting current in said device, a plurality of auxiliary keep-alive electrodes in said converter, a second source of exciting current energized by current flow in said converter, means for connecting said second source of current to said auxiliary keep-alive electrodes and means responsive to current flow to said auxiliary keep-alive electrodes to inhibit current flow to said first-mentioned keep-alive electrode.

11. An electric current conversion system comprising two dissimilar electrical circuits, a vapor electric device having a plurality of anodes and a cathode of vaporizable reconstructing material therein, transformer means for coupling said device to said circuits, an exciting electrode in said converter, a body of resistance material secured to said exciting electrode and extending into said cathode, said body having a resistance such that the potential necessary to produce an appreciable current therethrough is materially higher than the potential necessary to maintain an arc between said exciting electrode and said cathode and means for impressing an exciting potential between said exciting electrode and said cathode.

12. In combination with a vapor-electric device fed by transformer means including an interphase transformer, an excitation system comprising an exciting electrode in said device, a source of exciting current connected to said electrode, a make-alive electrode electrically connected to said electrode and extending into contact with the cathode of said device for initiating an exciting arc, auxiliary exciting electrodes in said device, an auxiliary winding on said interphase transformer and means for connecting said auxiliary winding to said auxiliary electrodes.

13. In combination with a vapor-electric device fed by transformer means including an interphase transformer, an excitation system comprising an exciting electrode in said device, a source of exciting current connected to said electrode, a make-alive electrode electrically connected to said electrode and extending into contact with the cathode of said device for initiating an exciting arc, auxiliary exciting electrodes in said device, an auxiliary winding on said interphase transformer and means for connecting said auxiliary winding to said auxiliary electrodes, and make-alive electrodes connected to each of said auxiliary electrodes and extending into contact with the cathode of said device.

14. In combination with an electric current conversion system comprising a plurality of dissimilar electrical circuits, a vapor electric converter including a plurality of anodes and a vaporizable cathode for controlling current flow between said circuits, an exciting system compris-
